UNITED STATES PATENT OFFICE.

GEORGE E. WHEELER, OF BURLINGTON, IOWA, ASSIGNOR TO THE BURLINGTON SEPARATOR CO., OF BURLINGTON, IOWA.

CHURN.

Application filed July 30, 1926. Serial No. 125,988.

This invention relates to a churn, one of the objects being to provide a device of this type having a dasher designed to revolve at a high speed, the action being such that a 5 continuous flow of fresh air will be set up downwardly into the fluid contained within the device and thence outwardly in thin sheets so as to quickly break up the fatty globules and reduce the liquid contents of the 10 container to butter in the shortest possible time.

A further object is to combine with the rotary dasher a novel form of breaker or baffle whereby agitation of the liquid contents 15 of the container is greatly increased during the rotation of the dasher. A further object is to provide a dasher utilizing a tubular stem which serves the purpose of an air flue or conductor whereby, through the centrifugal action of the rotating dasher, a current 20 of air downwardly into the fluid will be set up and the air delivered outwardly into the fluid from the margin of the dasher head.

A further object is to provide a dasher 25 head the parts of which can be separated readily for the purpose of cleaning or replacing them.

Another object is to provide simple and 30 efficient means for coupling the dasher to and uncoupling it from its driving mechanism.

With the foregoing and other objects in view which will appear as the description proceeds, the invention resides in the combination and arrangement of parts and in the 35 details of construction hereinafter described and claimed, it being understood that changes in the precise embodiment of the invention herein disclosed may be made within the scope of what is claimed without departing 40 from the spirit of the invention.

In the accompanying drawings the preferred form of the invention has been shown.

In said drawings,

Figure 1 is a section through a churn embodying the present improvements.

Figure 2 is a top plan view thereof.

Figure 3 is an enlarged vertical section through the dasher.

Figure 4 is a bottom plan view of the dasher.

Figure 5 is a plan view of the upper end of the dasher.

Figure 6 is a section on line 6-6, Figure 8.

Figure 7 is an enlarged section through a

portion of the washer head showing the means employed for holding the disks against relative rotation.

Referring to the figures by characters of reference 1 designates a ring like base provided with an upstanding annular flange 2, thereby providing a circular seat. A portion of the flange 2 can be cut away to provide an outlet 3 for fluid accumulating in the seat and extending from the base at diametrically opposed points are ears 4 in which are seated the lower ends of upstanding rods or posts 5. A frame 6 is extended outwardly from the base at a point preferably midway between the ears 4 and anchored in this frame are the lower ends of upwardly extending rods or posts 7 the upper ends of which are secured within an arm 8 extending downwardly from one end of a tubular casting 9. This casting is provided at one end with a housing 10 having a cover plate 11 for closing one side thereof, said plate being formed integral with a cross head 12 fixedly secured to the upper ends of the rods or posts 5.

A bearing member 13 is seated in the upper portion of the cross head 12 and an angular shaft 14 is mounted to slide and rotate therein, this shaft being provided at its upper end with a knob 15 or the like whereby it can be shifted longitudinally. The lower end of the shaft is mounted to slide and rotate within a bearing member 16 in the lower portion of the cross head and extending from the lower end of the shaft is a coupling head 17. Shaft 14 is slidably mounted within a gear 18 within the housing and this gear is designed to rotate with the shaft. A spring 19 is mounted on the shaft and bears at its upper end against the bearing member 13 while its lower end is designed to thrust against shaft 14 so as to hold said shaft normally projected downwardly. By pulling upwardly on the knob 15 the shaft 14 can be elevated against the action of spring 19 so as to retract the coupling member 17 into the lower portion of the housing.

Bearing members 20 are arranged within the end portions of the tubular casting 9 and journaled within these members is a shaft 21 one end of which has a gear 22 located in the housing 10 and constantly meshing with the gear 18. A small pinion 23 is provided at the other end of the shaft 21 and meshes with an internal gear 24 which is journaled on a

stud 25 extending from the arm 8. This gear has a radial arm 26 provided with a handle 27 whereby the gear can be rotated by hand and motion thus transmitted through gear 23 to the shaft 21. This shaft, in turn will transmit motion through gears 22 and 18 to the shaft 14 so that the coupling member 17 will thus be revolved at a high speed.

The seat provided by the base 1 and the flange 2 is designed to receive the base portion of a cylindrical container 28 which can be formed of glass, earthenware or any other suitable material. This container is provided, at the center of its bottom, with a boss 29 formed with a recess 30. A drain opening 31 can be formed in the wall of the container, this opening being normally closed by any suitable means such as a plug 32 or the like.

Arranged upon the inner surface of the wall of the container at desired intervals are breakers or baffles each of which consists of a strip 33 preferably of wood and provided with transverse openings 34. The lower ends of these strips bear upon the bottom of the container 28 while the upper ends are formed with tongues 35 to which are secured metal clips 36. These clips are adapted to embrace and grip upon the upper edge portion of the container 28 so as thus to hold the breakers or baffles firmly positioned within the container.

The principal feature of the present invention is the dasher. This dasher includes a tubular stem 37 open at its ends and provided, at its lower end, with a circular disk 38. This disk is provided with segmental depressions 39 and recesses 40 are formed in the bottoms of the depressions by striking portions of the metal upwardly. This is clearly indicated in Figure 7.

The upper end of the tube 37 is extended between short fingers 41 projecting from wings 42 which are integral with a cap 43 having a central outstanding boss 44. These wings 42 are spaced apart and their ends constitute shoulders 45 against which the upper end of the tube 37 abuts. Cap 43 and boss 44 constitute a nut for engaging the threaded upper end portion of a rod 46 the lower end portion of which is extended through the center of the bottom disk 47 of the dasher head. This bottom disk has nodes 48 struck upwardly therefrom and adapted to be seated within the recesses 40. Radial angular channels 49 are pressed downwardly into the disk and are so located that when the nodes 48 are seated in the recesses 40 these channels will be disposed under the disk 38 at points between the segmental depressions 39. Disk 47 has a nut 50 integral with the center portion thereof and to which the rod 46 is secured, the lower end of this rod being rounded as at 51 so as to constitute a bearing for engagement with the wall of recess 30.

The upper end of boss 44 has a diametrical groove 52 and this groove is designed to receive the coupling member 17.

In practice the dasher is inserted into the container 28 and the lower end 51 of rod 46 is placed in the recess 30. The shaft 14 is then lifted so as to permit the insertion of the cap 43 and boss 44 under the coupling member 17 after which said shaft 14 is released and spring 19 will seat the coupling member 17 within the groove 52. Thus the dasher will be coupled to its drive mechanism. The cream or other liquid to be treated is placed in the container and gear 26 is then rotated. This will cause rotation of the dasher at a high speed and the centrifugal force set up through the dasher head will cause fresh air to flow downwardly between the wings 42 into the tubular stem 37 and thence outwardly

in thin spaced sheets through the spaces provided between the disks 38 and 47 directly above the radial grooves 49. Air thus delivered in thin sheets will be forced outwardly into the fluid, each relatively narrow sheet of air sweeping outwardly under the sheet of air immediately preceding it and as these successive sheets of air act upon the fluid they will quickly aerate it, break up the fatty globules, produce a swirling action of the fluid, and the fluid, in turn, by sweeping against and past the breakers or baffles 33, will be further disintegrated. Consequently the production of butter will be greatly accelerated. It might be stated that by providing the grooves or depressions 49, the transverse area of each sheet of air delivered from the dasher head will have a transverse configuration approximating that of the space between the dashers. In other words portions of the sheet of air will be thicker than other portions. While this is only momentary it has been found that it produces a much greater agitation of the liquid than would be possible should the sheet of air be of uniform thickness. Furthermore the walls of the depressions impart greater momentum to each sheet of air than would be possible should these depressions not be utilized. Consequently each sheet of air will be thrown farther into the fluid than would be the case should the bottom disk be formed with a flat surface. It is to be understood of course that various changes may be made in the proportions and shapes of some of the parts of this device and that while the mechanism disclosed for driving the dasher is the preferred construction, other types of mechanism may be employed.

The breakers can be removed readily from the container for the purpose of cleaning them and by lifting the shaft 14, the coupling member 17 can become disengaged from the boss 44 so that the entire dasher can thus be removed readily from the container. By unscrewing the rod 46 from the boss 44 and cap 43, the wings 42 can be removed from engage-

ment with the tubular stem 37 and rod 46 with its disk 47 can be separated from the disk 48 and the stem 37. Thus the several parts can be easily cleaned and repaired.

5 What is claimed is:

1. In a churn a dasher including a tubular stem, a member having spaced wings engaging one end of the stem and providing air inlets between them, a disk at the other end of
- 10 the stem having depressions, a bottom disk bearing against the depressions to provide air outlets therebetween, cooperating interfitting means upon the disks for holding them against relative rotation, and an adjustable
- 15 connection between the bottom disk and the stem engaging member for binding the disks together.
2. In a churn a dasher including a tubular stem, a disk at one end of the stem having annularly spaced segmental depressions, said stem opening through the disk, a bottom disk resting flat against the depressions, those portions of the bottom disk between the depressions of the first named disk being formed
- 25 with radial depressions, cooperating interfitting means in the contacting portions of the disk for holding said disks against relative rotation, a rod fixedly secured to the bottom disk and extending longitudinally
- 30 through the stem, a cap constituting a nut

engaging that end of the rod remote from the disk, radial wings extending from one face of the nut having shoulders for engagement with the adjacent end of the stem, and driving means detachably connected to the 35 cap.

3. In a churn a dasher including a tubular stem, a rod extending therethrough, a disk carried by one end of the stem having annularly spaced segmental depressions, a disk 40 fixedly connected to the rod and normally fitted against said depressions, those portions of the disks between the depressions cooperating to provide outlets for air, cooperating means in the depressions and the adjacent 45 disks for holding the two disks against relative rotation while in contact, a cap engaging the other end of the rod and constituting a nut, radial wings extending from the cap toward the stem, said wings having free end 50 portions lapping the stem to center it about the rod, there being shoulders on the wings for thrusting against the stem, thereby to bind the disks together and hold them assembled with the stem and rod, the said parts 55 being separable when the cap is loosened.

In testimony that I claim the foregoing as my own, I have hereto affixed my signature.

GEORGE E. WHEELER.
